CLAIM

The ornamental design for an endoscope, as shown and described.

DESCRIPTION

FIG. 1 is a back, top, and left side perspective view of the endoscope, showing the new design;

FIG. 2 is a top view thereof;

FIG. 3 is a bottom view thereof;

FIG. 4 is a left side view thereof;

FIG. 5 is a right side view thereof;

FIG. 6 is front view thereof; and,

FIG. 7 is a back view thereof.

The ornamental design which is claimed is shown in solid lines in the drawings. Any broken lines in the drawings depict environmental subject matter only and form no part of the claimed design.
